United States Patent

Des. 236,796
Patented Sept. 16, 1975

236,796

MOP PAIL

Fritz Deusche, St. Louis, Mo., assignor to Schlueter
Manufacturing Company, St. Louis, Mo.

Filed Nov. 21, 1973, Ser. No. 418,099

Term of patent 14 years

Int. Cl. D7—07

U.S. Cl. D7—187

FIG. 1

FIG. 2

FIG. 1 is a top plan view of the mop pail, showing my new design, and

FIG. 2 is an isometric view of the mop pail of FIG. 1. The bottom is flat and plain and the opposite sides are identical to those shown.

I claim:

The ornamental design for a mop pail, substantially as shown and described.
